ANTISKID FINGER CLIP

George Hubert Eives, Brooklyn, N. Y., assignor
to Rives Neverslip, Inc., Brooklyn, N. Y., a corporation of New York

Application August 1, 1939, Serial No. 287,716

4 Claims. (Cl. 294—25)

The present invention relates to antiskid devices of the type adapted to be applied to the fingers of an operator for the purpose of facilitating the dealing of cards, counting of paper money or coupons, the turning of the pages of a book, and other similar manipulations of flexible sheet materials.

Among the objects of the present invention is to provide a new and improved antiskid finger clip of the general type above referred to, which is simple and light in construction and inexpensive to manufacture, which lends itself easily to mass production, which can be easily applied to the fingers of the operator and comfortably used, which permits use of a pencil or pen while the clip is in position, which is easily adjustable to fit fingers of any size or shape, which is sanitary and easily washable, which can be safely used without injuring the fingers or injuring the manipulated sheets, which does not affect the sense of touch nor stop the circulation of blood, and which is rugged, durable and efficient in use.

Various other objects of the invention will be apparent from the following particular description, and from an inspection of the accompanying drawing, in which:

Fig. 1 is a perspective showing flexible sheets in the process of being successively turned by a finger, on which a finger clip embodying the present invention is applied.

Fig. 2 is a plan view of one form of finger clip embodying the present invention, and shown on a greatly enlarged scale.

Figs. 3 and 4 are sections taken on lines 3—3 and 4—4 of Fig. 2.

Fig. 5 is a perspective of the metal frame piece forming the core of the finger clip, and

Fig. 6 is a longitudinal section of a smaller form of finger clip, embodying the present invention, and shown on an enlarged scale, said section being taken along a plane coextensive with one face of the metal frame piece.

In the specific form of the invention shown in Figs. 1 to 5, the finger clip 10 comprises a jacket 12 of rubber or similar resilient material, molded and vulcanized around a metal frame piece 11 to form a firm inseparable unit therewith, and constituting a reinforcing core for said jacket.

This frame piece 11 comprises a flat strip of easily bendable or pliant non-corrosive, non-toxic metal, desirably stamped from a ribbon-like blank strip. I have found ductile Monel metal containing approximately about 68% nickel, 28% copper and about 2% iron highly desirable for that purpose.

The frame core piece 11 is provided with a series of aligned comparatively narrow elongated slots 13, three being shown, extending longitudinally and medially of said piece, and inter-

spaced by transverse sections 14 of the metal. Near the ends, the frame piece 11 is provided with shorter slots 15, having a width which is greater than that of the slots 13, and which extends a substantial distance across said frame piece, so that the sections 16 of said frame piece on opposite sides of said slots 15 will be comparatively narrow. With this construction, the frame piece 11 will be weakest for transverse bending at the sections thereof across the slots 15 for the purpose to be hereinafter described.

The outer ends of the two outside elongated slots 13 are desirably enlarged to form circular openings 17 to receive pins (not shown), for centering and supporting the frame piece 11 in the mold during the process of molding and vulcanizing the rubber around said frame piece.

In the process of forming the complete article, the frame piece 11 as shown in Fig. 5 is centrally supported in a mold in the manner above described, with the rubber to be vulcanized and molded, surrounding said frame piece, and the assembly is treated in said mold under the usual molding and vulcanizing temperature and pressure of rubber. In the present case, the pressure may be 1800 lbs. per square inch, and the temperature 289° F. By this process, the rubber will form an integral jacket 12, firmly embracing the frame piece 11, and having sections 19 extending through the slots 13 and 15, so that said rubber jacket and said frame piece are interwoven into one firm inseparable unit.

The transverse frame piece sections 14 interspacing the slots 13, as well as the transverse sections 20, spacing the series of slots 13 from the end slots 15, are highly desirable, for they serve as anchoring abutments for the sections 19 of the rubber extending therethrough, so that slippage of the jacket 12 with respect to said frame piece is prevented. These transverse frame sections 14 and 20 also serve to impart transverse rigidity to the frame piece 11, especially necessary to effectively resist the vulcanizing and molding pressure tending to spread said frame piece transversely.

In order to prevent the embedded frame piece 11 from cutting into the rubber jacket 12, and to prevent the possibility of any portion of said frame piece from cutting into the fingers, if it should become accidentally exposed, the outer edges of said frame piece are desirably slightly rounded. This rounding of the outer edges may be accomplished by the rolling action which forms the ribbon-like blank strip from which the individual frame pieces 11 are made.

The inner face 21 of the rubber jacket 12, adapted to be placed directly in contact with the finger to which the finger clip 10 is applied, is desirably smooth, so that the clip may be

comfortably worn on said finger. The outer face 22 of the rubber jacket 12, adapted to directly engage the sheets to be manipulated, is provided with an antiskid frictional surface 23. 5 This antiskid surface is desirably formed by an embossed design, in the form of letters or members molded into the rubber, and indicating source of origin, size or the like.

The rubber jacket 12 may be of any desired 10 color. It may be highly colored, as for instance blue, to present a pleasing contrasting appearance with respect to the finger to which it is applied, or it may conform in color with that of the finger nails to satisfy the aesthetic emotions of the 15 women. If desired, it may be flesh color, so that it is inconspicuous when applied to the fingers.

In applying the finger clip to an operating 20 finger of one hand, the straight clip as shown in Fig. 2 is held between the thumb and the index finger of the other hand, with the smooth inner side 21 of said clip in engagement with the inner face of said operating finger, and the clip bent by the holding fingers around said operating finger, so that the clip will assume substantially 25 the contour of the operating finger as shown in Fig. 1. In order to more firmly hold the clip on the operating finger, the ends thereof may be bent inwardly more sharply, either to conform with the contour of the outer surface of the operating 30 finger or to make the ends of the clip bear inwardly on said outer surface to more firmly hold the clip in position. The transverse weakened sections at the end of the frame piece 11 formed by the slots 15 as already explained permit 35 the ends of the clip to be bent more acutely than the intermediate portion for the purpose above specified.

In the operation of the clip 10 as for instance in counting paper money or dealing cards from 40 a stack, the antiskid surface 23 of the clip mounted on the thumb of the operator is made to bear against the top sheet of the stack, while said thumb is moved in a direction to cause slippage of said sheet with respect to the remainder 45 of the stack. Since the clip 10 is very light and of simple construction, the operator is hardly conscious that he is wearing said clip, except for its effectiveness in slipping the sheets successively from the stack. The finger on which the clip is 50 mounted still retains its sense of touch, especially necessary in the counting of paper money.

The clip shown in Figs. 1 to 5 may be applied to the thumb or any other finger according to the whim of the particular operator, or use to 55 which it is to be put. If, for instance, it is desired to use the clip on the little finger as for instance for the purpose of turning over the sheets of a book, and if the clip shown in Figs. 1 to 5 is too large for the size of said finger, a smaller clip 60 may be provided as shown in Fig. 6. This clip, with its metal frame piece 11a embedded in a rubber jacket 12a, is in all respects the same as that shown in Figs. 1 to 5, except that its size is much smaller, and there are two elongated slots 65 13 instead of three, in order to accommodate for the shorter length of the frame piece used.

The clip of the present invention is free from all comparatively complicated attachments such as clamps and the like, and the interwoven 70 separable connection between the frame piece

and the rubber jacket free from adhesive and the like prevents possible slippage of the jacket with respect to the frame piece, and possible separation of the parts. The metal portion of the clip is entirely concealed, so that it does not 5 come in contact with the fingers or the sheets being manipulated, to cause injury to the same, and the clip may be easily washed and dried without affecting its efficient operation. Furthermore, the clip can be easily applied requiring a 10 mere finger manipulation, and is easily adjustable for application to fingers of different size and shape.

As many changes could be made in the above construction, and many apparently widely different 15 embodiments of this invention could be made without departing from the scope of the claims, it is intended that all matter contained in the above description or shown in the accompanying drawing shall be interpreted as illustrative 20 and not in a limiting sense.

Having thus described my invention, what I claim as new and desire to secure by Letters Patent is:

1. An antiskid finger clip for manipulating 25 sheet-like material, comprising a one-piece jacket of resilient material, and a frame core of pliant metal, embedded in said jacket, and having one or more apertures, said jacket having sections thereof extending through said apertures to 30 interlock said frame core and said jacket into an inseparable unit.

2. An antiskid finger clip for manipulating 35 sheet-like material, including a strip-like rubber jacket, and a strip-like frame core of pliant metal embedded in said jacket and extending substantially the full length thereof, said frame core being provided at opposite ends thereof with slots forming transverse weakened sections, to 40 permit the ends of said clip to be easily bent transversely more acutely than the intermediate section thereof.

3. An antiskid finger clip for manipulating 45 sheet-like material, comprising a one-piece strip-like rubber jacket, and a strip-like frame core of pliant metal, embedded in said jacket and extending substantially the full length thereof, said frame core having one or more elongated slots 50 extending lengthwise thereof in its intermediate portion, and said rubber jacket having portions thereof extending through said slot or slots.

4. A finger clip for manipulating sheet-like material, comprising a one-piece strip-like rubber jacket, having a substantially smooth surface on one side thereof and an embossed design 55 on the other side affording an antiskid surface, and a strip-like frame core of ductile metal, embedded in said rubber jacket, and extending substantially the full length thereof, said frame core having a series of elongated slots in the intermediate portion thereof, extending lengthwise of said frame core and separated by transverse sections of said core, and slots near opposite ends of said core, forming weakened transverse sections to permit easy transverse bending of said 60 core ends, said jacket having sections thereof extending through all of said slots, whereby said core and said jacket are interwoven and interlocked into an inseparable unit.

GEORGE HUBERT RIVES. 70
